(57) **CLAIM**

The ornamental design for an end treatment for a ring mechanism, as shown and described.

DESCRIPTION

FIG. 1 is a perspective view of an end treatment for a ring mechanism showing my new design;

FIG. 2 is an enlarged fragmentary perspective view of FIG. 1;

FIG. 3 is a front elevation view thereof;

FIG. 4 is a right side elevation view thereof, the left side elevation view being a mirror image; and,

FIG. 5 is a bottom plan view thereof.

The broken lines shown in the drawings indicate structure and features which form no part of the claimed design.
